Archie E. Shearer, La Habra, Calif.

Application November 17, 1936, Serial No. 111,249

8 Claims. (Cl. 312—193)

This invention relates to improvements in cabinets.

The general object of this invention is to provide a novel cabinet comprising a plurality of compartments and wherein novel means is provided for locking the closures of the compartments.

Another object of this invention is to provide a novel concealed locking means for compartment members.

Other objects and the advantages of this invention will be apparent from the following description taken in connection with the accompanying drawings wherein:

Fig. 1 is a front elevation of my cabinet;

Fig. 2 is a side elevation;

Fig. 3 is a fragmentary section taken on line 3—3 of Fig. 2 showing one drawer opened;

Fig. 4 is a section taken on line 4—4 of Fig. 1 showing the door opened;

Fig. 5 is an enlarged fragmentary section taken on line 5—5 of Fig. 1;

Fig. 6 is an enlarged fragmentary section taken on line 6—6 of Fig. 4;

Fig. 7 is an enlarged fragmentary section taken on line 7—7 of Fig. 4;

Fig. 8 is an enlarged fragmentary section taken on line 8—8 of Fig. 4;

Fig. 9 is an enlarged fragmentary section showing the concealed panel opening;

Fig. 10 is an enlarged fragmentary section showing one of the supports; and

Fig. 11 is a fragmentary section taken on line 11—11 of Fig. 5.

Referring to the drawings by reference characters I have shown my invention as embodied in a cabinet which is indicated generally at 10. This cabinet is particularly adapted for containing jewelry and other articles of value and may be placed upon a dresser or upon other suitable means.

As shown the cabinet includes a rear portion or back 11, ends 12, a bottom 13, and a front 14. The cabinet includes a lower portion 15 and an upper narrower portion 16. In the lower portion I provide a horizontal partition 17 which is spaced above and is parallel to the bottom 13 to provide a drawer space 18 in which I arrange a drawer 19 which is provided with suitable knob or handle 20 and which includes a recess or slot 21 in one of the drawer rails 22.

The partition 17 serves as the bottom of a compartment 23 which has a closure 24 hinged as at 25. This closure 24 includes a glass panel 26 so that the contents of the compartment 23 may be observed.

At one end of the compartment 23 a vertically extending wall 27 is arranged on which a top portion 28 is provided to therefore provide a chamber 29 in which operating mechanism to be presently described is arranged. The hinge 25 is mounted on a transverse member 30 from which a supplemental back member 31 extends downwardly and engages the upper surfaces of the partition 17 to form a back for the compartment 23 and the chamber 29. In the rear of the supplemental back member 31 I have shown a partition 32 which in conjunction with the partition 17 forms a recess 33 in which a drawer 34 is slidably mounted. This drawer 34 as shown in Fig. 3 has ends 35 and the drawer 34 is of length 15 corresponding to that of the cabinet so that the outer faces of the end portion 35 are flush with the ends 12 of the cabinet when the drawer is in closed position.

Adjacent the member 30 I hinge a secret closure 20 member 36 which is mounted on pivots 37 on the ends 12 to swing from the position shown in Fig. 4 to the position shown in Fig. 9. The closure member 36 has a bevelled end 38 engaging a similarly bevelled portion 39 on the member 25 30 previously described.

The top of the closure member 36 and the inner surface of the rear 11 may be preferably covered with a layer 40 of material such as velvet so that a suitable background is provided for a compartment 41 which is arranged above the closure member 36 and in front of the back 11 is provided.

This compartment 41 is provided with a front door 42 which is hinged as at 43 to one end wall 35 12 and this closure 42 is preferably provided with a glass panel 44 as shown. The upper end of the compartment 41 is closed by a partition 45 which has a closure 46 therefor which is hinged as at 47 to the back 11. The closure 46 includes a back 48 which is preferably opaque and the ends 40 and front 49 are provided with slots 50 in which a glass panel 51 is arranged. This panel 51 is spaced from the back 48 so that slot 52 for a picture or other object is provided. The lower end 45 of the closure 46 is bevelled as at 53 to engage a bevelled stop 54 arranged on the partition 45.

Within the compartment 41 I provide a plurality of post members 55 each of which, as shown, includes a sleeve 56 in which a screw 57 is inserted. This screw extends into the back 11 as shown in Fig. 10. The posts 55 may serve to support jewelry or other articles.

In order to lock the various compartments securely I provide a locking device in the chamber 55

29. As shown this device includes a working lever 60 mounted on a pivot 61. This lever includes an arm 62 on which an operating member 63 is pivoted. This operating member 63 includes an upwardly extending portion 64 which passes through a rabbet 65 in the wall 28 which serves as a top for the chamber 29. The member 63 also includes a lower portion 66 which extends through a hole 67 in the partition 17 and projects into the recess 21 in the drawer rail previously described. A spring 68 normally urges the member 63 upwardly.

In use the closure 24 is moved downwardly until a hasp 68' thereon fits over an apertured member 68'' and in this position the closure 24 is closed with the lower face of the closure engaging the portion 64 of the operating member 63 and depressing the operating member so that the end 66 thereof engages in the recess 21 in the drawer.

This motion of the operating member 63 rocks the lever 60 about its pivot 61 and rocks link 69 on the rear of the lever upwardly. This link 69 passes through a recess 70 in the member 39 and fits in a recess 71 in the bottom rail of the door 42 thus holding this door securely locked. At the same time the rocking of the lever 60 moves a link 89 rearwardly through a recess in the supplemental back 21 and into a hole 82 in the drawer 34 thus securely locking this drawer.

The apertured holding member 68' is preferably pivotally mounted between two plates 93 as shown in Fig. 5 and includes an upwardly extending portion 84 which has a hook 85 thereon adapted to engage within a recess 86 in the hasp member 68''. It will thus be apparent that after the hasp member has been removed from the member 68' the latter must be turned before the closure 24 can be opened and thus the various compartment closures released. A suitable padlock 87 engages in the aperture in the member 68'.

It will be noted that the ends 12 extend beyond the adjacent portions of the cabinet as clearly shown in Fig. 2 and that these ends may be made by a continuous saw cut thus avoiding the time required where sharp angles are included. The parts of the cabinet are preferably made of wood and can be secured together by 50 screws, nails, or glue.

From the foregoing description it will be apparent that I have invented a cabinet which can be economically made and which is highly effective for the intended purpose.

55 Having thus described my invention I claim:

1. In a cabinet, a housing including ends, back, a front, and a bottom, a drawer slidable forwardly in the lower portion of said housing, said housing including a compartment above said drawer, a closure for said compartment, a partition in the rear of said compartment to provide a second compartment, a drawer slidable laterally of the housing and in said second compartment, said housing including a third compartment above said second compartment, a door hinged about a vertical axis for closing said third compartment, and means operated by closing of said closure to lock said door and said drawers.

2. In a cabinet, a housing including ends, back, a front, and a bottom, a drawer slidable in the lower portion of said cabinet, a partition above the drawer forming a compartment thereabove, said compartment including a supplemental back member spaced from said first mentioned back member, a transverse member above said sup-

plemental back member, a closure for said compartment and hinged to said transverse member, the upper portion of said housing including a second compartment, a door for closing said second compartment, a lever pivoted in said housing, a link pivotally mounted on said lever and including an upwardly directed portion engageable by said pivoted closure to rock said lever and move said link, said first mentioned partition having a hole through which said link extends, said drawer having a recess to receive said link, a second link on said lever, said door having a recess disposed to be engaged by said second link, and locking means to lock said closure.

3. In a cabinet, a housing including ends, back, a front, and a bottom, said cabinet including a lower portion which is deeper than the upper portion, a drawer slidable in the lower portion of said cabinet, a partition above the drawer forming a compartment thereabove, said compartment including a supplemental back member spaced from said first mentioned back member a transverse member above said supplemental back member, a closure for said compartment and hinged to said transverse member, a partition in the rear of said supplemental back member and spaced above said first mentioned partition to provide a second compartment, a second drawer slidable in said second compartment, said back and ends forming a third compartment, said third compartment having a partition at the upper end thereof, a door for closing the compartment below said last mentioned partition, a diagonally disposed hinged closure above said last mentioned partition, an operating lever, a plurality of links mounted on said lever and movable to locking engage said drawers and said door, one of said links engaging said first mentioned closure when the latter is closed, and means to hold said closure closed.

4. In a cabinet, a housing including ends, back, a front, and a bottom, a drawer slidable in the lower portion of said cabinet, a partition above the drawer forming a compartment thereabove, said compartment including a supplemental back member spaced from said first mentioned back member, a transverse member above said supplemental back member, a closure for said compartment and hinged to said transverse member, a partition in the rear of said supplemental back member and spaced above said first mentioned partition to provide a second compartment, a second drawer slidable in said second compartment, a closure hinged above said second compartment, said back and ends above said last mentioned closure forming a third compartment, said third compartment having a partition at the upper end thereof, a door for closing the compartment below said last mentioned partition, a closure above said last mentioned partition, locking means serving to lock said door and said drawers closed when the first mentioned closure is closed, means to hold said first mentioned closure closed, said last mentioned means including a pivoted apertured member on the front of the cabinet and a hasp on said closure, said pivoted apertured member including a locking catch and said hasp including a recessed portion to receive said locking catch.

5. In a cabinet, a housing including ends, back, a front, and a bottom, said cabinet including a lower portion which is deeper than the upper portion, a drawer slidable in the lower portion of said cabinet, a partition above the drawer

- forming a compartment thereabove, said compartment including a supplemental back member spaced from said first mentioned back member, a transverse member above said supplemental back member, a closure for said compartment and hinged to said transverse member, said back and ends forming a second compartment, said second compartment having a partition at the upper end thereof, a door for closing said compartment below the partition, a hinged closure above said last mentioned partition, an operating lever, a plurality of links mounted on said lever and movable to lockingly engage said drawer and said door, one of said links engaging 5 said closure when the latter is closed, and means to hold said closure closed, said last mentioned means including a pivoted apertured member on the front of the cabinet and a hasp on said closure, said pivoted apertured member including 10 20 a locking catch and said hasp including a recessed portion to receive said locking catch.
6. In a cabinet, a housing including ends, back, a front, and a bottom, said cabinet including a lower portion which is deeper than the upper portion, a drawer slidable in the lower portion of said cabinet, a partition above the drawer forming a compartment thereabove, said compartment including a supplemental back member spaced from said first mentioned back member, a transverse member above said supplemental back member, a closure for said compartment and 25 hinged to said transverse member, a partition in the rear of said supplemental back member and spaced above said first mentioned partition to 30 provide a second compartment, a drawer slid- 35 able in said second compartment, a closure hinged above said second compartment, said last men- 40 tioned closure having a covering thereon, said covering extending over said back, said back and 45 ends above said last mentioned closure forming a third compartment, said third compartment having a partition at the upper end thereof, a door hinged to one of said ends for closing said third compartment below the partition, a dia- 50 ginally disposed hinged closure above said last mentioned partition, locking means serving to lock said door and said drawers closed when the first mentioned closure is closed, means to hold 55 said first mentioned closure closed, said last mentioned means including a pivoted apertured member on the front of the cabinet and a hasp on said closure, said pivoted apertured member including a locking catch and said hasp includ- 60 ing a recessed portion to receive said locking catch.
7. In a cabinet, a housing including ends, back, a front, and a bottom, a drawer slidable in the lower portion of said cabinet, a partition above the drawer forming a compartment there- 65 above, said compartment including a sup- 60 plemental back member spaced from said first men- 65 tioned back member, a transverse member above said supplemental back member, a closure for said compartment and hinged to said trans- 65 verse member, said last mentioned closure hav- 5 ing a covering thereon, said covering extending over said back, said back and ends above said last mentioned closure forming a second compartment, said second compartment having a 10 partition at the upper end thereof, a hinged door for closing said second compartment below the partition, a hinged closure above said last mentioned partition, a partition forming a cham- 15 ber in said first compartment, a lever pivoted in said chamber, a link pivotally mounted on said lever and including an upwardly directed por- 20 tion engageable by said pivoted closure to rock said lever and move said link downwardly, said first mentioned partition having a hole through 25 which said link extends, said drawer having a re- 30 cess aligning with said link when the drawer is closed, a second link on said lever, said door having a recess disposed to be engaged by said second link, said supplemental back having an 35 aperture therein, said links serving to lock said door and said drawer closed when the closure is closed and means to hold said closure closed.
8. In a cabinet, a housing including ends, back, a front, and a bottom, a drawer slidable in the lower portion of said cabinet, a partition above the drawer forming a compartment thereabove, said compartment including a supplemental back member spaced from said first mentioned back member, a transverse member above said supplemental back member, a closure for said compartment and hinged to said transverse member, a partition in the rear of said supplemental back member and spaced above said first mentioned partition to provide a second compartment, a 35 second drawer slidable in said second compartment, a closure hinged above said second compartment, said last mentioned closure having a covering thereon, said covering extending over 40 said back, said back and ends above said last mentioned closure forming a third compartment, said third compartment having a partition at the upper end thereof, a door for closing said third compartment below the partition, a dia- 45 ginally disposed hinged closure above said last mentioned partition, a partition forming a cham- 50 ber in said first compartment, a lever pivoted in said chamber, a link pivotally mounted on said lever and including an upwardly directed portion engageable by said pivoted closure to rock said 55 lever, said first mentioned partition having a hole through which said link extends, said drawer having a recess aligning with said link when the drawer is closed, a second link on said lever, said door having a recess disposed to be 60 engaged by said second link, said supplemental back having an aperture therein, a third link on said lever and passing through said supplemental back aperture, said second drawer having a hole to receive said third link when the drawer is 65 closed, said links serving to lock said door and said drawers closed when the closure is closed and means to hold said closure closed.
